UNITED STATES PATENT OFFICE

158,522 COMBINATION TABLE AND CHAIRS

James J. Smith and Charles L. Chew,
Gloucester City, N. J.

Application May 5, 1949, Serial No. 2,459

Term of patent 3½ years

(Cl. D33—14)

To all whom it may concern:

Be it known that we, James J. Smith and Charles L. Chew, citizens of the United States of America, residing at Gloucester City, in the county of Camden and State of New Jersey, have invented a new, original, and ornamental Design for a Combination Table and Chairs, of which the following is a specification, reference being had to the accompanying drawing, forming part thereof.

Figure 1 is a perspective view of a combination table and chairs, showing our new design.

Fig. 2 is a bottom plan view.

Fig. 3 is a rear elevational view.

Fig. 4 is an end elevational view.

Fig. 5 is a transverse sectional view on line 5—5 of Fig. 3.

We claim:

The ornamental design for a combination table and chairs, as shown.

JAMES J. SMITH.
CHARLES L. CHEW.
